(57) **CLAIM**

An ornamental design for an electrical connector, as shown and described.

DESCRIPTION

FIG. 1 is a front, top, and right side perspective view of an electrical connector;

FIG. 2 is a front elevational view thereof;

FIG. 3 is a rear elevational view thereof;

FIG. 4 is a right side elevational view thereof;

FIG. 5 is a top plan view thereof;

FIG. 6 is a bottom plan view thereof; and,

FIG. 7 is a sectional view thereof along a line 7—7 in FIG. 2.

A left side elevational view of the electrical connector is omitted because it is presented symmetrical to the right side elevational view of FIG. 4.
